UNITED STATES PATENT OFFICE.

ARTHUR TAYLOR, OF BOSTON, MASSACHUSETTS.

DESIGN FOR A VEGETABLE-MASHER CASING.

SPECIFICATION forming part of Design No. 35,422, dated December 10, 1901.

Application filed September 16, 1901. Serial No. 75,619. Term of patent 14 years.

To all whom it may concern:

Be it known that I, ARTHUR TAYLOR, a citizen of the United States, residing at No. 34 Magnolia street, in the city of Boston, in the county of Suffolk and State of Massachusetts, have invented and produced a new and original Design for a Vegetable-Masher Casing, of which the following is a specification, reference being had to the accompanying drawings, forming part thereof.

My design is peculiar in the shape or configuration of the several parts and in their relative proportions, as well as in the surface ornamentation or appearance.

The upper part of my masher-casing has an oblong rectangular outline, tapering inwardly on each of its four sides, as in section A of the several figures, which comprises about one-third the entire height of the casing. Below this is section B of the casing, having parallel vertical front and back plates 25 5 and 6, the edges of each converging downwardly and terminating in a nearly semicircular curve, as in Figs. 1 and 2. The lower part of section B, between the parallel front and back, has a reticulated surface 7, resembling netting.

A raised cruciform figure 8, Figs. 1 and 3, having a protruding central hub 9, with a cylindrical opening through it, is formed on the front plate 5, while the back plate 6 has a 35 corresponding perforation 10 in line therewith. Dovetailed diverging ribs 11 project from the back plate, one at each side of said perforation.

I claim as my invention—

The design for a vegetable-masher casing, substantially as described and shown.

In testimony whereof I have affixed my signature in presence of two witnesses.

ARTHUR TAYLOR.
